Primary Examiner — Michael A. Pratt(74) *Attorney, Agent, or Firm* — Birch, Stewart, Kolasch & Birch, LLP(57) **CLAIM**

The ornamental design for a wireless headset communications device, as shown and described.

DESCRIPTION

1. Wireless headset communications device

1.1 : Perspective

1.2 : Front

1.3 : Back

1.4 : Left

1.5 : Right

1.6 : Top

1.7 : Bottom

1.8 : Reference

The broken lines shown in figures 1.1 through 1.8 illustrate portions of the wireless headset communications device that do not form a part of the claimed design. The broken lines showing of a wearer in figure 1.8 illustrates environment which forms no part of the claimed design.

1 Claim, 8 Drawing Sheets(56)
